ALBERT R. THOMPSON, OF SAN JOSE, CALIFORNIA, ASSIGNEE TO ANDERSON-BARNGROVER MFG. CO., OF SAN JOSE, CALIFORNIA, A CORPORATION OF CALIFORNIA.

COOKER.

1,250,244.

Specification of Letters Patent. Patented Dec. 16, 1917.

Application filed January 11, 1912. Serial No. 741,470.

To all whom it may concern:

Be it known that I, ALBERT R. THOMPSON, a citizen of the United States, residing at San Jose, in the county of Santa Clara and State of California, have invented certain new and useful Improvements in Cookers, of which the following is a specification.

My invention relates to cookers used in the canning art.

10 The object of my invention is to provide a cooker of compact dimensions which nevertheless has a sufficiently extensive can-path to give the required "time of cook"; and which lends itself perfectly to varying this time without changing the speed of the machine, or altering its temperature.

My invention consists in the novel cooker which I shall now fully describe by reference to the accompanying drawings, in 20 which—

Figure 1 is a top view of my cooker, the box being broken away in part, to show the interior parts.

Fig. 2 is a vertical section of my cooker.

Fig. 3 is an end view of the same, the box being in section to show the interior parts.

Fig. 4 is a sectional detail, enlarged, on the line $x-x$ of Fig. 1, showing can-feed.

15 1 is the heating box. Heat is supplied by any suitable medium, such, for example, as hot water, live steam or hot air. For the sake of illustration, I herein show a steam coil 2 which may, if perforated, admit live steam to the box, or if imperforate may heat the air, or may heat water in the box. Neither the means for heating, nor the medium employed, forms any part of my invention, and will therefore need no further description.

20 3 is a drain from the box controlled by a cock 4. Within the box 1 are fixed the cross bars 5, here shown in Fig. 3 as at four equidistant points. To these cross bars is secured the fixed guide-rail 6, which is in 25 the shape of a helix. It is, in its best form, a bar of T-section, secured by its arm portions to the cross bars 5, so that its leg portion projects inwardly. The helical rail 6 has such a pitch that its coils are separated

30 by a distance sufficient to support the cans 7 lengthwise upon the opposing arm portions of adjacent coils, thereby forming a spiral track or path in which the cans may be advanced in continuous helical course

from their entrance to their discharge, said cans being supported by the arm portions of the T-section rail and directed in their progress by the leg portion of said rail.

8 is a shaft which lies in the axis of the helical rail 6. This shaft is mounted for rotation in suitable bearings 9 on the box 1, and said shaft, within the box, carries the ends or heads 10 between the peripheries of which are secured the rails 11 which extend in the general line of the shaft 8. The shaft, heads and rails thus constitute a reel, which rotates within the fixed helical rail 6. The reel-rails 11 are also best formed as bars of T-section secured by their arm-portions to the heads 10, with their leg portions projecting outwardly; and they are separated from each other by a distance to admit the diameter of the cans so that they support the cans between opposing arm portions of adjacent rails, and said reel-rails 15 are separated from the helical rail 6 by a distance sufficient to admit the cans.

It will now be seen that a continuous track or path or pocket for the cans is provided, said path being bordered exteriorly by the arm portions and the leg portion of the helical rail 6 and interiorly by the arm-portions and leg-portions of the reel rails 11.

It follows that if a can be introduced, say at the upper portion of the machine, to 35 its support upon the arm-portions of adjacent reel rails 11, at one end of the reel, it will upon the rotation of said reel be carried around by the leg of one of said rails 11, and will at the same time be advanced 40 by the contact of its ends with the leg of the fixed helix rail 6, until, passing its first quarter of revolution it changes by gravity its support to the arm-portions of the helix rail, which support continues through its 45 lower arc of revolution, until upon its rising course it changes its point of support back again to the arm-portion of the reel rails 11, and so on throughout the length of the path or track or pocket from one end of 50 the machine to the other.

Thus a plurality of lines of cans 7 end to end are continually advancing between adjacent reel-rails and all the lines are revolving about the axis 8; the number of revolutions depending upon the length of the helix bar 6.

A point of advantage is to be noted as

follows:—The cans when passing through their upper arc of revolution rest upon the reel rails 11 and are out of contact with the arm-portions of the helix 6; they therefore have no rotation on their own axes; but when passing through their lower arc of revolution, said cans then rest upon the arm-portions of the helix 6, and as said helix is fixed, the pushing movement of the leg portions of the reel rails 11 will cause the cans to roll on the helix, thereby, giving them a rotation on their own axes. This is found to be of advantage in stirring up the can contents during the cooking.

15 Another feature of importance in my cooker is as follows:—It is adapted for what is termed in the canning art “different times of cook.” This means that it is necessary to cook the contents of the cans for different times according to their needs. In practice this result is reached by changing the speed of the conveying mechanism, or changing the degree of heat. But such means are not satisfactory. With my machine I can give 20 the different “cooks” without changing either the speed of the machine or the temperature of the box. This I can do by simply introducing the cans at different points along the helical path so that they will remain 25 in the cooker a longer or a shorter time as may be desired. To provide for this variable introduction of the cans, I have means as follows:—

30 Supported at one side of the upper portion of the box 1 is a feed trough 12 in which I have shown a traveling cable 13 as the means for advancing the cans 7 in the trough.

In the inner wall of the trough are plural 35 openings 12' with which communicate chutes 14, one chute for each opening, the communication being controlled by gates 15. I have here shown but two chutes 14, though it will be understood that more may be provided.

40 The chutes have a slight down grade and they pass through the wall of the box 1, their inner ends terminating at the helix rail 6, which latter at this place has, as shown in Fig. 1 at 16, the arm portions of adjacent coils cut out sufficiently to admit the length of the cans between them, so that said cans may pass through between the helix coils and find initial support upon 45 the reel rails 11.

In the outer wall of the trough 12, opposite the communications of the chutes 14 are the switches 17. These consist of angled bars pivoted at 18 by the extremity of one 50 arm to the outside of the trough wall. The angle of each switch is adapted to swing inwardly to lie in the path of the cans, and to swing out again to retire from said path.

55 A cross pin 19 to lie outside the trough wall and adapted to be passed through either

the angle of the switch or through the extremity of its free arm, serves to hold the switch in operative or inoperative position.

Suppose now that the cans have to be cocked for their longest time. The first 70 switch 17 is thrown into the trough and each can meeting it, will be diverted to enter the first chute 14, its gate 15 being open. Down this chute it rolls by gravity into the machine. But if a shorter cook be desired, the 75 first gate 15 is closed, the first switch is opened, the second switch is thrown in, and the second gate opened, so that the cans will no proceed to the second chute and will be directed into the machine farther 80 along in the helical path so as to remain in the machine a shorter time, and this without having to vary the speed of the reel or the temperature of the box.

At the other end of the box and within 85 it is the fixed discharge rail 20 which leads from the final coil of the helix rail 6 to the delivery chute 21 through which the cans successively pass to the carrier belt 22 in the delivery trough 23.

90 24 is the drive shaft with pulley 25. Upon the shaft 24 is the worm 26 meshing with the worm gear 27 on the reel shaft 8.

I claim:

1. In a cooker, the combination of a heating box; means within the box for advancing the cans therethrough, said box having successive can-inlets communicating at successive points with the can-path, and means for supplying the cans to a given inlet at 100 will, comprising a feed trough with means for advancing the cans therein, said trough having successive communications with said heating box inlets, gates controlling said communications, and switches in the feed 105 trough to divert the cans to said communications.

2. In a cooker, the combination with its heating box, of an annular series of rails; a helically directed rail concentric with said 110 annular series of rails and complementing the same to form tracks for the cans; means for imparting to one of the components of said tracks axial rotation relatively to the other to effect the advance of the cans on 115 said tracks; separate successive can inlets in said heating box communicating with successive points in the length of said tracks; and means for supplying the cans to a given inlet at will, comprising a feed trough with 120 means for advancing the cans therein, said trough having successive communications with said heating box inlets, gates controlling said communications, and switches in the feed trough to divert the cans to said 125 communications.

3. A cooker comprising a heating box having an outlet for the cans; a revoluble annular series of longitudinal rails within the box; a fixed helically directed rail with- 130

- in the box concentric with said annular series of rails and spaced therefrom to complement said rails and form therewith tracks for cans in a continuous helical path through the box; a fixed diverting rail within the box coacting with the final coil of the helical rail to direct the cans successively to the box outlet; separate successive can inlets in said heating box communicating with the successive points in the length of the rails of the revoluble annular series; and means for supplying the cans to a given inlet at will, comprising a feed trough with means for advancing the cans therein, said trough having successive communications with said heating box inlets, gates controlling said communications, and switches in the feed trough to divert the cans to said communications.
4. In an apparatus for treating packaged goods the combination of a substantially closed casing comprising a cooking zone through which the packages are moved, the said casing being provided with three or more openings in communication with the cooking zone at different points along the path for the packages and through which the packages may pass so that the operator may select different openings for the packages whereby the length of travel of the packages within the cooking zone may be varied at will and separate closures permitting the operator to close the openings not selected.
5. In an apparatus for treating packaged goods, the combination of a substantially closed chamber comprising a cooking zone through which the packages are moved, the inclosing wall of said chamber being provided with three or more openings in communication with the cooking zone at different points along the path, means for causing the packages to pass through such of said openings as the operator may select whereby the length of travel of the packages within the cooking zone may be varied at will, and separate closures whereby the operator may close any of said openings not selected.
6. In an apparatus for treating packaged goods, the combination of a substantially closed casing comprising a cooking zone through which the packages are moved, the said casing being provided with at least three openings constituting inlets and outlets in communication with the cooking zone constituting three places through which the packages may be passed as the operator may select whereby the length of travel of the packages within the cooking zone may be varied at will, and means for closing that opening in the casing through which the packages may pass which is not selected.
7. In an apparatus for treating packaged goods the combination of a substantially closed casing comprising a cooking zone through which the packages are moved and being open at different parts to permit the passage of packages through the casing at at least three different points, a track extending through the cooking zone for receiving the packages, means for moving the packages along the track, said track having at least three parts at different points arranged to permit the passage of packages therethrough, said parts registering with said open parts of the casing and means for closing that open part in the casing through which the packages may pass which has not been selected for the passage of the package therethrough.
- In testimony whereof I have signed my name to this specification in the presence of two subscribing witnesses.
